CLAIM

The ornamental design for a connector, as shown and described.

DESCRIPTION

FIG. 1 is a side elevational view of a connector according to the present invention showing the two halves of the connector attached to each other, the undisclosed side being identical;

FIG. 2 is a left end elevational view of the connector shown in FIG. 1;

FIG. 3 is a right end elevational view of the connector shown in FIG. 2;

FIG. 4 is a side elevational view of the connector shown in FIG. 1 showing the two halves of the connector separated from each other, the undisclosed side being identical;

FIG. 5 is a left end elevational view of the right connector half shown in FIG. 4; and,

FIG. 6 is a right end elevational view of the connector half shown in FIG. 4.
